US00D757659S

(12) **United States Design Patent**
Besana et al.

(10) **Patent No.:** **US D757,659 S**
(45) **Date of Patent:** **** May 31, 2016**

(54) **CIRCUIT BREAKERS**

(71) Applicant: **ABB S.p.A.**, Milan (IT)

(72) Inventors: **Stefano Besana**, Terno d'Isola (IT);
Lucio Azzola, Bergamo (IT)

(73) Assignee: **ABB S.p.A.**, Milan (IT)

(**) Term: **14 Years**

(21) Appl. No.: **29/489,919**

(22) Filed: **May 5, 2014**

Related U.S. Application Data

(62) Division of application No. 29/459,135, filed on Jun. 26, 2013, now Pat. No. Des. 707,636, which is a division of application No. 29/383,747, filed on Jan. 21, 2011, now Pat. No. Des. 687,387, which is a division of application No. 29/341,449, filed on Aug. 5, 2009, now Pat. No. Des. 633,446.

(57) **CLAIM**

The ornamental design for circuit breakers, as shown and described.

DESCRIPTION

FIG. 1 is a front perspective view circuit breakers showing the new design;

FIG. 2 is a front view thereof;

FIG. 3 is a rear view thereof;

FIG. 4 is a top view thereof;

FIG. 5 is a bottom view thereof;

FIG. 6 is a left view thereof; and,

FIG. 7 is a right view thereof.

The broken line portion of figure drawings is included to show portions of the article that forms no part of the claimed design.

1 Claim, 7 Drawing Sheets
